UNITED STATES PATENT OFFICE

HARVEY A. BERNHARDT, OF CHICAGO, ILLINOIS

DESIGN FOR A SANITARY ASH RECEPTACLE

Application filed November 4, 1929. Serial No. 33,321. Term of patent 3½ years.

To all whom it may concern:

Be it known that I, HARVEY A. BERNHARDT, a citizen of the United States, residing at Chicago, in the county of Cook and State of Illinois, have invented a new, original, and ornamental Design for a Sanitary Ash Receptacle, of which the following is a specification, reference being had to the accompanying drawing, which is a perspective view of the article showing my new design.

I claim:

The ornamental design for a sanitary ash receptacle, as shown.

In testimony whereof I affix my signature.

HARVEY A. BERNHARDT.
